FISHING ROD HOLDER

William J. Stahl, Chatham, N.J., assignor to National Manufacturing Company, Inc., Chatham, N.J.

Filed Oct. 15, 1970, Ser. No. 25,494

Term of patent 14 years

Int. Cl. D6—04

U.S. Cl. D33—17

FIG. 1 is an isometric view of a fishing rod holder showing my new design in a partly open position and with a portion of the resilient material omitted to clearly illustrate the configuration of the hook elements,

FIG. 2 is a view taken from one side thereof,

FIG. 3 is a bottom plan view thereof in the closed position,

FIG. 4 is a top plan view thereof,

FIG. 5 is an end view thereof somewhat enlarged, and FIG. 6 is an end view thereof opposite from FIG. 5.

I claim:

The ornamental design for a fishing rod holder, substantially as shown and described.
